UNITED STATES PATENT OFFICE.

JAMES F. SUTTERFIELD, OF GOOSE CREEK, TEXAS.

OIL BURNER.

Application filed March 1, 1924. Serial No. 696,263.

To all whom it may concern:

Be it known that I, JAMES F. SUTTERFIELD, a citizen of the United States, residing at Goose Creek, in the county of Harris and State of Texas, have invented certain new and useful Improvements in Oil Burners, of which the following is a specification, reference being had to the accompanying drawings.

10 This invention relates to an improved oil burner of the vaporizer type and one object of the invention is to provide an oil burner which is provided with improved vaporizer means and which includes oil containing 15 pockets so that when the burner is initially placed in operation the pockets may contain a reserve supply of oil which will be converted into gas after the vaporizer has been heated by oil burning in the oil pan and will 20 supply gas which will be ignited and will burn for some time, thereby making it unnecessary for the operator to watch the burner when it is initially lighted and turn the oil on as soon as the oil in the pan has 25 been consumed.

Another object of the invention is to so construct this burner that the flame from the burning gas may be directed towards certain of the reservoir pockets and act in 30 a very effective manner to convert this reserve supply of oil into a gas.

Another object of the invention is to so construct this burner that one of the reservoir forming pipes may be extended to a 35 point close to the pan so that this pocket may be thoroughly heated by a burning wick placed in the pan and saturated with oil.

Another object of the invention is to so 40 construct this oil burner that the pipe line may be formed of ordinary pipe sections connected by couplings and the pockets for the reserve oil also formed of pipe sections connected with the pipes forming the vaporizer portion of the burner by couplings.

Another object of the invention is to so 45 construct this burner that the flame spreader may be suspended about the outlet nozzle by means of a yoke suspended from pipes forming the side arms of the vaporizer portion of the burner.

This invention is illustrated in the accompanying drawings, wherein:

50 Figure 1 is a view showing the improved burner principally in side elevation and partially in vertical section.

Figure 2 is a top plan view of the improved burner with the flame spreader left off.

Figure 3 is a view showing the flame spreader in side elevation and suspended from the side pipes of the vaporizer, the side pipes being shown in section.

Figure 4 is a longitudinal vertical sectional view through the burner.

Figure 5 is a view in side elevation showing a construction having two of the burners provided above a pan.

Figure 6 is a top plan view of the pan shown in Figure 3.

This burner is provided with a pan 1 which will be preferably rectangular in shape and provided with the usual side and end flanges or walls so that oil may be placed in this pan in order to initially heat the pipes forming the vaporizer of the burner. At one corner the pan is provided with an elevated platform forming portion 2 which is of sufficient height to prevent the oil in the pan from flowing over this platform. This platform is provided with an opening through which extends a coupling 3 which serves to connect the burner with a supply pipe 4 leading to a tank 5 in which the supply of oil will be kept. This supply pipe 4 may be provided with a valve 6 adjacent the tank 5 and with a second valve 7 adjacent its connection with the coupling 3 so that this valve 7 may be easily reached when operating the burner.

The burner is provided with a substantially U-shaped vaporizer forming portion which is positioned in spaced relation above the pan 1 and is provided with spaced side arms 8 and 9 which are formed of pipes and are connected with depending pipes 10 and 11 by suitable couplings 12. The pipe 11 extends downwardly and is connected with the coupling 3 so that this pipe 11 communicates with the supply pipe 4. The pipe 10 has its lower end connected with a pipe 13 by means of a coupling 14 of the elbow type and this pipe 13 extends along the pan 1 and terminates intermediate the length and width of the pan. A coupling 15 is connected with this pipe 13 and extends upwardly and has connected with its upper end a short pipe or nipple 16 carrying a nozzle 17 in which an outlet opening is provided. A wick 18 is placed in the pan and extends longitudinally beneath the pipe 13 and coupling 15 and extends beyond this coupling 15 to a

point adjacent the other end of the pan. Each of the pipes 8 and 9 is formed of end sections which are connected by a T coupling 19 and these T couplings 19 are provided 5 with depending arms which carry short pipe sections 20 closed at their lower ends by caps 21 and forming pockets for receiving a reserve supply of oil. At the ends opposite the couplings 12 the pipes 8 and 9 carry couplings or elbows 22 and between these couplings 22 there has been provided a T coupling 23 connected with the couplings 22 by short nipples 24. This coupling 23 is also provided with a depending arm with which 10 is connected a pipe 25. This pipe 25 which extends downwardly from the coupling 23 also forms a pocket for receiving a supply of oil. It should be noted, however, that this pipe 25 is of greater length than the pipes 20 and is of such length that the cap 26 which closes its lower end will be positioned very close to the extended end portion of the wick 18. Therefore, when the wick is saturated with oil and this oil is ignited the 15 burning oil will thoroughly heat the pipe 25 and also thoroughly heat the pipe 13 and coupling 15 and nozzle carrying pipe 16. The oil in the pipe 25 will therefore be expanded and a portion of this oil will flow 20 through the vaporizer and supply oil to the pipe 13. When the gas is generated it is desired to have the flame deflected and, therefore, there has been provided a flame spreading disc 27 which is positioned above the 25 nozzle 17 and suspended from a yoke 28, the ends of which rest upon the pipes 8 and 9. This deflector will cause the flame to be spread so that the flame will serve to thoroughly heat the pipes 8 and 9 and also heat 30 the pipes 20 forming the depending oil receiving pockets.

When this improved burner is in use it will be set up as shown with the pipe 4 leading from the oil supply tank and connected 45 with the coupling 3 at the lower end of the pipe 11. The pan may be positioned in the fire box of a cook stove or at any other point where it is desired to make use of the device. The valve 7 may then be opened and a sufficient quantity of oil permitted to pass 50 through the pipes to cause a portion of the oil to flow out of the nozzle 17 and into the pan to soak the wick and if necessary provide a certain amount of unabsorbed oil in the pan. By having the wick formed of asbestos the oil may be burned without the wick being consumed. As the oil flows 55 through the pipes forming the burner the pipes 20 and 25 will also be filled so that a 60 reserve supply of oil will be provided. A match will then be applied to the wick so that the oil will be ignited and as this oil burns it will thoroughly heat the pipe 13 and pipe 25. The heating of the pipe 25 will 65 cause the oil contained in this pipe to be ex-

panded and as this oil expands it will flow into the pipe 8 and down the pipe 10 into the pipe 13 so that additional oil is fed to the pipe 13 and will be converted into gas which will pass out through the nozzle 17 70 and become ignited. This gas will be directed upwardly as it passes through the nozzle and when ignited the flame will strike the disc 27 and will be deflected so that the pipes 20 and 8 and 9 and also the pipe 25 75 will be thoroughly heated by the burning gas. The oil in the pipes 20 and 25 will therefore be caused to give off a gas which will pass through the pipes 8, 10 and 13 to the pipe 16 and out through the nozzle 17. 80 In view of the fact that the pipes 20 and 25 carry a quantity of oil this oil will supply gas to the burner for a relatively long length of time. Therefore, the operator does not need to stay close to the burner when it is 85 initially lighted so that he can be sure to turn the valve on as soon as the oil in the pan is consumed and then light the gas as it passes out through the nozzle. After he has lighted the oil in the pan he can leave the 90 burner and as soon as the pipes 20 and 25 are heated a sufficient amount the oil in these pipes will be converted into gas which will be ignited from the burning oil in the pan. As soon as this gas is burning a roaring noise 95 will be caused which will attract the attention of the operator and he can then open the valve 7 a sufficient amount to supply oil to the burner to take the place of the oil which is consumed. This oil passes through 100 the pipes and is vaporized in passing through the pipes 8 and 9 so that it passes into the pipes 10 and 13 as a gas and then passes upwardly through the pipe 16 and through the outlet of the nozzle 17. It will therefore be 105 seen that there has been provided an oil burner which is very efficient in operation and it can be very easily operated.

If it is desired to construct this burner for use in large stoves or furnaces and the like 110 the pan 1^a may be made of a greater length and a platform 2' provided intermediate the length of the pan with a partition 29 extending from this platform to the other side of the pan. The pipe 4 could then be provided with branch pipes 30 and 31 leading from it to the couplings 3 of burners of a duplicate construction and provided with valves 7 and 7'. It might also be constructed 115 so that any number of these burners could 120 be provided above a pan of suitable dimensions.

What is claimed is:—

1. An oil burner comprising a pipe line 125 having a U-shaped portion and a portion extending beneath the U-shaped portion and provided with an upwardly projecting nozzle directed between the arms of the U-shaped portion and in spaced relation to the bight of the U-shaped portion, said pipe line being 130

- provided in the arms and bight thereof with T's to the stem portions of which are connected depending oil receiving pockets, a spreader supported from the arms of the 5 U-shaped portion and against which the gas generated in the U-shaped portion impinges to be spread thereby and brought into contact with said U-shaped portion and with said depending oil receiving pockets.
- 10 2. An oil burner comprising a pipe line having a U-shaped portion and a portion extending beneath the U-shaped portion and provided with an upwardly projecting nozzle directed between the arms of the U-shaped 15 portion and in spaced relation to the bight of the U-shaped portion, said pipe line being provided in the arms and bight thereof with T's to the stem portions of which are connected depending oil receiving pockets, a 20 spreader supported from the arms of the U-shaped portion and against which the gas generated in the U-shaped portion impinges to be spread thereby and brought into contact with said U-shaped portion and with 25 said depending oil receiving pockets, one of said depending oil receiving pockets having its lower end extending below the level of the nozzle.
3. An oil burner comprising a pipe line 30 having a U-shaped portion and a portion extending beneath the U-shaped portion and provided with an upwardly projecting nozzle directed between the arms of the U-shaped portion and in spaced relation to the bight 35 of the U-shaped portion, said pipe line being provided in the arms and bight thereof with T's to the stem portions of which are connected depending oil receiving pockets, a spreader supported from the arms of the 40 U-shaped portion and against which the gas
- generated in the U-shaped portion impinges to be spread thereby and brought into contact with said U-shaped portion and with said depending oil receiving pockets, one of said depending oil receiving pockets having 45 its lower end extending below the level of the nozzle and a pan against which the lower end of said oil pocket engages, said pocket being connected with the bight portion of the U-shaped portion of the pipe line and 50 forming a support therefor, the ends of the arms of the U-shaped portion having depending pipe portions, one of which is connected with the nozzle and the other of which is adapted for engagement with a 55 source of supply, said depending pipe portions having engagement with the pan to thereby support the ends of the arms of said U-shaped portion.
4. An oil burner comprising a pipe line 60 having a U-shaped portion and a portion extending beneath the U-shaped portion and provided with an upwardly projecting nozzle directed between the arms of the U-shaped portion and in spaced relation to the bight 65 of the U-shaped portion, said pipe line being provided in the arms and bight thereof with T's to the stem portions of which are connected depending oil receiving pockets, a 70 spreader supported from the arms of the U-shaped portion and against which the gas generated in the U-shaped portion impinges to be spread thereby and brought into contact with said U-shaped portion and with 75 said depending oil receiving pockets, said depending oil receiving pockets being provided with removable caps.

In testimony whereof I hereunto affix my signature.

JAMES F. SUTTERFIELD.
